UNITED STATES PATENT OFFICE.

SCOTT H. HULL, OF OSKALOOSA, IOWA.

DESIGN FOR A SLIDE-D.

SPECIFICATION forming part of Design No. 33,742, dated December 18, 1900.

Application filed November 19, 1900. Serial No. 37,072. Term of patent 14 years.

To all whom it may concern:

Be it known that I, SCOTT H. HULL, a citizen of the United States of America, and a resident of Oskaloosa, Mahaska county, Iowa, 5 have invented a certain new and original Design for Slide-D's, of which the following is a specification.

The object of this invention is to provide a new and original design for slide-D's.

My invention consists of the design for a slide-D hereinafter set forth, pointed out in my claim, and illustrated by the accompanying drawings, in which—

Figure 1 is a face view of a slide-D embodying my design. Fig. 2 is an end view of a slide-D embodying my design. Fig. 3 is a transverse sectional view of a slide-D embodying my design.

In the design as shown the numeral 10 designates a plate relatively thin and curved or concavo-convex in cross-section. The curvature of the plate 10 is on the arc of a circle and extends throughout approximately one-third of said circle, and the edges of the

plate determining the extent of the arc are 25 plane and parallel with each other. The end portions of the plate are slightly thicker than the body portions thereof, thus producing ribs 11 12, tapering to the plane edges of the plate. The yoke 13 leads radially from the 30 central portions of the ribs 11 12 and arches across and is spaced apart from the body of said plate on a line midway between the plane edges of the plate. The end portions of the yoke 13 are approximately straight and are 35 connected by curved corner portions 13^a 13^b to an approximately straight bar or central portion 13^c.

I claim as my invention—

The design for a slide-D, substantially as 40 herein shown and described.

Signed at Des Moines, Iowa, this 6th day of October, 1900.

SCOTT H. HULL.
